UNITED STATES PATENT OFFICE.

WILLIAM MATNEY, OF STONE, KENTUCKY.

CAR-WHEEL-RERAILING BLOCK.

1,404,877.

Specification of Letters Patent. Patented Jan. 31, 1922.

Application filed April 21, 1921. Serial No. 463,109.

To all whom it may concern:

Be it known that I, WILLIAM MATNEY, a citizen of the United States, and a resident of Stone, in the county of Pike and State 5 of Kentucky, have invented certain new and useful Improvements in Car-Wheel-Rerailing Blocks, of which the following is a specification.

This invention relates to car wheel rerailing blocks.

The object of the invention is to provide a pair of companion blocks, whereby a railroad car which has been derailed may be expeditiously replaced upon the track.

Other objects relating to details of construction will appear in the detailed description to follow.

For the purpose of clearness hereinafter, one of the blocks will be referred to as the 20 inside block and the other block, as the outside block.

The invention is illustrated by way of example in the accompanying drawings, in which:

25 Figure 1 is a top plan view of a section of a railroad track and illustrating the use of my invention.

Figure 2 is a top plan view of the inside block, and showing the same connected to 30 the adjacent rail,

Figure 3 is a top plan view of the outside block,

Figures 4 and 5 are side elevations of the inside and outside blocks shown in Figures 35 2 and 3, respectively,

Figures 6 and 7 are front end elevations of the inside and outside blocks shown in Figures 2 and 3, respectively,

Figure 8 is a transverse vertical section 40 taken substantially on the line 8—8 of Figure 5.

Referring to the drawings more particularly, 10 indicates generally the inside block, and 11 the outside block. Each block is 45 substantially triangular in shape and having its forward end rounded as at 12. Each end is provided with a recess or offset 13. The blocks are of the same thickness and may be cast hollow or solid as shown. The bottom face of each block has an offset extending along each side thereof, as indicated at 14; also each upper corresponding edge of the blocks is provided with an offset or recess as shown at 15. In each bottom face 55 of each block there is also provided a channel or recess 16 which intersects with the offsets 14. The top surface of each block

near the rear end slopes downwardly as at 17, and near the end of this sloped surface there is provided a pair of openings as indicated at 18. The openings 18 are adapted to receive railroad spikes for a purpose which will later become apparent. Centrally of the top surfaces of each block there is formed a rib 19, the rib on the block 10 60 extending the entire length thereof while the rib on the block 11 extends only to a center point of the block. Forward to the rib 19 on the block 11 there is provided an arcuate recess 20 which is adapted to receive 70 and seat the enlargement 21 formed on the lower side of the platform 22. The platform 22 is adapted to freely tilt upon the enlargement 21 as a pivot. The ends of the platform 22 are tapered to correspond with 75 the sides of the block 11, they however projecting slightly beyond the sides of the block 11. An opening 23 is formed through the enlargement 21 and likewise a similar opening is formed in each adjacent side wall of 80 the recess 20, said openings being adapted to receive a pin 24 whereby the platform is held from becoming displaced.

Each block has secured to its forward end 85 a pair of links 25 and also a similar pair of links 26 are secured to each block at a point centrally of the recess or channel 16 formed in the lower face of said blocks. The pair of links in each case are secured by means of a staple as shown. On the outer link 90 member of each pair there is pivotally connected the one end of an L-shaped clip 27, said clip having its other end portion provided with an opening as indicated at 28.

Referring to Figure 1, 29 indicates a number 95 of railroad ties and 30 and 31, sections of rails laid upon said ties. At 32 there is shown an axle on each end of which there is journaled a railroad car wheel 33. The wheels are shown as derailed. The inside 100 block 10 is placed on the inside of the rail 30, as shown, and secured in position by means of the spikes 33. The outside block 11 is placed on the outer side of the rail 31 and likewise secured in position by the means of 105 spikes 33, as shown. Also these blocks may be additionally anchored by securing the L-shaped members 27 to the rails 30 by the spikes 35, as shown. These additional anchors are of considerable advantage in case 110 the ties have been smashed or otherwise partly demolished by the car wheels at the time of derailment.

In replacing the car wheel upon the track

the operation is as follows: The wheels 33 roll upon the blocks and their flanges engage the blocks on the inner side of the guide ribs 19. As the wheels continue to rotate the car is elevated and when the wheel upon the block 11 is rolled upon the platform 22 upon one end thereof, said platform will tilt and its corresponding end engage upon the top surface of the rail 31. This action will impart to the car wheel a slight side movement and due to the inclination of the platform 22, the car wheels will then take the path shown in the dotted lines 34 in Figure 1 and become replaced or railed.

15 The obvious purpose of the tilting platform 22 is to raise the wheel which rolls thereon sufficiently so that its flange may pass over the adjacent rail. The inside block 10 would of course not require this as the flange of the 20 car wheel which rotates upon this block need not be lifted over the adjacent rail.

I claim:

1. An outside block for rerailing railroad car wheels, comprising a substantially triangular shaped casting, a guide-rib formed on the top surface thereof and extending from its end having the greatest cross section to a central point of block and a tilttable platform mounted on said block forward of the end of the guide-rib.

2. An outside block for rerailing railroad car wheels comprising a substantially triangular shaped casting, a guide-rib formed on the top surface thereof at substantially 35 right angles to the base, said guide-rib extending from the base to an intermediate point of the block, a tilttable platform mounted forward of the end of said rib and upon the top surface of said block, the ends of 40 said platform extending beyond the sides of the block.

3. An outside block for rerailing railroad car wheels, comprising a substantially triangular shaped casting with the top surface 45 of its base end curved downwardly, a guide-rib formed upon the top surface of the casting and extending from the base to an intermediate portion thereof and a tilttable platform mounted upon said block forward 50 to the end of the guide-rib.

4. An outside block for rerailing railroad car wheels, comprising a substantially triangular shaped casting, having the top surface of the base end curved downwardly, a 55 guide-rib formed on the top surface extending from the base end of the block to an intermediate point thereof, a platform forward to the end of said rib, a pivot for said platform adapted to permit tilting movement thereof toward the side of the block, said pivoting means being supported by the block.

5. An outside block for rerailing railroad

car wheels, comprising a substantially triangular shaped casting having a guide-rib 65 formed on the top surface thereof, extending from its base end to an intermediate point of the block and having an arcuate recess formed in the top surface of said block forward to the end of said rib, a platform having an enlargement on the bottom thereof adapted to seat in said arcuate recess and means by which said platform may be held against displacement.

6. In combination an outside and an inside block for rerailing a pair of railroad car wheels, a guide-rib on the top surface of each block adapted to cooperate with the flanges of the car wheels to guide said wheels toward the rails and a tilttable platform on 80 the top surface of the outside block, the one end of which is adapted to rest upon the adjacent rail when tilted in a corresponding direction.

7. An outside block for rerailing railroad 85 car wheels comprising a casting adapted to be fitted against the side of a rail, a rib formed upon the top surface of the casting extending longitudinally thereof, and detachable means associated with the forward 90 end of the casting whereby upon being engaged by a car wheel an inward slanting surface upon the block will be formed.

8. In combination an outside and an inside block for rerailing a pair of railroad 95 car wheels, a guide-rib on the top surface of each block adapted to cooperate with the flanges of the car wheels to guide said wheels toward the rails, a tilttable platform on the top surface of the outside block, the one end 100 of which is adapted to rest upon the adjacent rail when tilted in a corresponding direction, and means by which said blocks may be detachably secured to the rails with which they are associated.

9. In combination an outside and an inside block for rerailing a pair of railroad car wheels, a guide-rib on the top surface of each block adapted to cooperate with the flanges of the car wheels to guide said wheels 110 toward the rails, a tilttable platform on the top surface of the outside block, the one end of which is adapted to rest upon the adjacent rail when tilted in a corresponding direction, and means by which said blocks may be held against longitudinal movement.

10. An outside block for rerailing railroad car wheels comprising a casting adapted to be fitted against the side of a rail, a rib formed upon the top surface of the casting 120 extending longitudinally thereof, and means associated with the forward end of the casting whereby upon being engaged by a car wheel an inward slanting surface upon the block will be formed.

WILLIAM MATNEY.
